UNITED STATES PATENT OFFICE

CHRISTOPHER J. ANDERSON, OF CHICAGO, ILLINOIS, ASSIGNOR TO BLAZEK COLD STORAGE DOOR COMPANY, OF CHICAGO, ILLINOIS, A CORPORATION OF ILLINOIS

DOOR-REENFORCING DEVICE

Application filed October 9, 1929. Serial No. 398,297.

This invention relates to a door reenforcing device designed primarily for use in the reenforcement of doors intended for cold storage rooms or the like, and the purpose of the invention is to provide attaching means for a diagonal metal brace bar which serves to prevent any direct transmission of temperature through the door, or sagging of the door.

10 The door is anchored at its upper end within the upper inner corner of the door, and at its lower end within the lower outer corner, and the device of the present invention is intended to be imbedded within the door framing in such a way as to secure a firm and solid anchorage at these points and to make provision for the attachment of the ends of the brace bar.

15 The device is designed with a view to affording convenience in insertion into place, and with a view to the avoidance of screws, bolts, or like connections. The device, furthermore, is designed to so engage the wooden frame of the door as to prevent splitting of 20 the wood when subjected to strains, and to afford a rigid, durable and efficient connection for the brace bar.

25 Further objects and details of the invention will appear from a description thereof, in conjunction with the accompanying drawings, wherein,

30 Figure 1 is a sectional detail of one of the door corners showing the anchoring device of the present invention inserted;

35 Fig. 2 is an inner face view of the door, with the lining partially broken away to reveal the brace bar; and

40 Fig. 3 is a perspective view of the anchor. The door, as shown, is of the style commonly employed in cold storage rooms or compartments, and comprises a vertical door side 10 upon each side of the door, which is reenforced on the inside by a stiffener 11 which affords a ledge or shelf 12 to which 45 the lining strips 13 are secured.

45 The outer face of the door is in the form of a panel 14 which is secured by tongue and groove connection to a stile 15, which in turn is screwed or otherwise rigidly secured to 50 the door side of the abutting stiffener. The

stile affords an overlapping flange 16 which receives a packing strip or gasket 17, which abuts against the face of the door casing. These details are common in the construction of doors of this character and need not be further described in detail. The door is preferably filled with cork insulation or other packing of the character used for such purpose.

55 The door is braced by means of a diagonal brace bar 18 of angle iron, comprising a backing flange 19 which abuts against the door panel, and a projecting flange 20 which extends inwardly toward the interior of the door. The ends of the brace bar extend closely to the corners and are secured at each end to an anchor 21 which particularly constitutes the subject matter of the present invention.

60 The anchor comprises a drum-shaped head 22 from which extends a neck 23 which is preferably of a thickness equal to the thickness of the head 22 and of less width. The neck 23 merges into a diagonally extending arm 24 of less thickness than the neck, to afford shoulders 25 on each side where the arm merges into the neck.

65 The arm terminates in a head 26 provided with an aperture 27 adapted to receive a bolt 28, the head 29 of which is countersunk into the backing flange 19 of the diagonal brace. The bolt passes through the aperture 27 and receives a nut 30 which serves to lock the anchor to the adjacent end of the brace bar and to bring the arm 24 and head 26 into flatwise relation to the backing flange 19. The anchor thus occupies a position within the angle of the diagonal brace and affords a firm and rigid attachment therefor.

70 The drum head 22 is fitted within a cylindrical recess 31 formed by drilling inwardly from the base of the door side before the attachment of the stile, and the neck 23 occupies a recess 32 cut into the stiffener 11.

75 The recess 32 is of reduced width but of equal depth with the recess 31 into which it merges, which configuring of the recesses affords space for the socketing of the anchor head and neck, allowing the arm 24 to project inwardly toward the interior of the door 80

in position to make connection with the adjacent end of the diagonal brace bar. The anchor thus fits snugly within the heavy side and stiffener of the door and serves to firmly 5 unite the brace bar with a heavy and rugged portion of the door structure at each of the two corners.

The anchor is inserted by merely slipping it inwardly before the stile is applied, and 10 when the stile is in place the anchor will be completely enclosed and imbedded within the woodwork of the door into which it fits snugly, so that no opportunity for movement or displacement is afforded.

15 The drum-shaped head is larger than the neck, and the strains are directed in a diagonal line, so that any tendency toward displacement will be resisted by an adequate thickness of wood to prevent splitting or enlarging of the apertures even when severe 20 strains are encountered.

The device is simple in construction, easy of application, inexpensive, and well adapted for the purpose intended.

25 I claim:

1. In combination with the structure of a door, a brace bar extending diagonally of the door structure to prevent sagging, and anchoring devices, one for each end of the diagonally extending brace bar, each anchoring device comprising an enlarged head imbedded within the door structure near one 30 of the corners thereof, and an outwardly extending neck terminating in an attaching member, and means for securing the attaching member to the proximate end of the brace bar.

2. In combination with the structure of a door, a brace bar extending diagonally of the door structure to prevent sagging, two anchoring devices, one for each end of the brace bar, each anchoring device comprising a drum-shaped head imbedded within the door structure, a neck outwardly extending 40 from the head; and an arm extending diagonally with respect to the neck, and means for attaching the arm to the proximate end of the brace bar.

3. In combination with the structure of a door, comprising sides, each provided with a cylindrical recess, the recesses being diagonally disposed with reference to the door structure, two anchoring devices having an enlarged drum-shaped head socketed within one of the recesses, and a neck extending from the head and terminating in a diagonally disposed arm, and means for securing the arm to the proximate end of the brace bar.

4. In combination with the structure of a door, comprising sides, each provided with a cylindrical recess, the recesses being diagonally disposed with reference to the door structure, two anchoring devices having an 55 enlarged drum-shaped head socketed within

one of the recesses, and a neck extending from the head and terminating in a diagonally disposed arm, and means for securing the arm to the proximate end of the brace bar, and a stile for each side of the door overlying the recess and serving to enclose the head of the anchor. 70

5. In combination with a door structure including sides, each provided with an inwardly extending cylindrical recess, the recesses being diagonally disposed with respect to the door structure, an anchoring device for each recess, each anchoring device comprising an enlarged drum-shaped head socketed within the recess, and a neck of reduced width extending inwardly toward the interior of the door structure and terminating in a diagonally disposed arm having an enlarged apertured head, and a brace bar of angle formation having the apertured head secured to 80 one of its flanges. 85

6. An anchoring device of the character described, comprising an enlarged head, a neck of reduced width projecting from the head and terminating in a diagonally extending arm provided with an apertured portion adapted to receive a bolt. 90

7. An anchoring device of the character described, comprising an enlarged drum-shaped head, a neck of reduced width projecting from the head and terminating in a diagonally extending arm provided with an apertured portion adapted to receive a bolt. 95

In witness that I claim the foregoing I hereunto subscribed my name this 31st day 100 of August, 1929.

CHRISTOPHER J. ANDERSON.
